Application September 2, 1947, Serial No. 771,578

16 Claims. (Cl. 73—32)

1

This invention relates to a densimeter and more particularly to a densimeter for measuring the densities of fluids.

Among the several objects of the invention may be noted the provision of a densimeter for accurately and continuously indicating the densities of fluids, both liquid and gaseous; the provision of a density meter which at all values of fluid densities will automatically compensate for temperature-induced density variations in a fluid being tested; the provision of a densimeter of this class which is adaptable to density indicating and control purposes; and, the provision of a densimeter of the class described which is dependable in operation and of reliable construction. Other objects will be in part apparent and in part pointed out hereinafter.

The invention accordingly comprises the elements and combinations of elements, steps and sequence of steps, features of construction and manipulation, and arrangements of parts which will be exemplified in the structures and methods hereinafter described, and the scope of the application of which will be indicated in the following claims.

In the accompanying drawings, in which one of various possible embodiments of the invention is illustrated,

Fig. 1 is a side elevation of a vibratory element of the present invention with its casing shown in section;

Fig. 2 is a vertical section taken on line 2—2 of Fig. 1, the top portion of the casing being broken away;

Fig. 3 is a horizontal section taken on line 3—3 of Fig. 2; and,

Fig. 4 is a circuit diagram.

Similar reference characters indicate corresponding parts throughout the several views of the drawings.

The present invention utilizes the principle that the natural resonant frequency of any vibratory element or system may be varied by a change in its mass. Thus, in accordance with the present invention the variation in frequency of a vibratory element or system is used to indicate density variations of fluids which are internally contained in such a vibratory element or system.

Referring now more particularly to Figs. 1 to 3, there is shown at numeral 1 a vibratory element or system. This vibratory element 1 includes two hollow tines 3 and 5 which are firmly affixed by brazing or a like method in a fixed base block 24. These tines have their walls thinned out at

2

28 so as to favor vibratory movements. The tine 3 is provided with a bottom 6 which by means of a connector 7 and adaptor 9 is connected to an inlet conduit 11. An adaptor 13 and an inlet fitting 15 are utilized to extend the passage of conduit 11 through a cup-shaped supporting base 17.

Tine 5 is similarly provided with a bottom cap 18, a connector 19, an adaptor 21, a conduit 23, an adaptor 25 and an outlet fitting 27. Tines 3 and 5 are supported by and extend through the block 24 which by means of a bracket 29 and bolts 31 is rigidly affixed to the base 17. Block 24 is provided with an internal passage to permit communication between the interior of tine 3 and the interior of tine 5. Suitable drain plugs 33 and 51 permit access for cleaning purposes.

Tine 3 contains a tube 35 having perforations 37 at its upper end and having a machined disc 39 rigidly affixed and sealed to its upper end. The lower end of tubing 35 is snugly but removably fitted into the bottom cap 6, to provide easy removal for cleaning purposes. The upper and lower surfaces of the disc 39 are sealed against the top edge of tine 3 by means of threaded cap 41.

Tine 5 is similarly provided with a tube 43 having perforations 45 and a disc 47 at its upper end. A removable cap 49 is similarly provided for tine 5. Caps 41 and 49 have affixed to their upper surfaces bolts 53. These bolts together with adjustment nuts 55 are utilized exactly to match the vibratory characteristics of tines 3 and 5.

An electromagnetic vibrating driver 57 is mounted on a bracket 58 and is positioned so as to act upon two magnetic shoes 59 which are mounted respectively upon tines 3 and 5. Microphones 61 and 63 are respectively supported by bracket 58 in juxtaposition to tines 3 and 5, respectively. The electrical output from the microphones 61 and 63 is conducted by means of wires 65 carried by a cable 67 which passes through the cup-shaped base 17. The electrical input to the electromagnetic driver 57 is carried by wires 69 of said cable 67. The entire assembly of the vibratory element 1 and its corresponding components are sealed by means of a casing 71. The cup-shaped base 17 may be mounted conveniently by means of a bracket 72.

Referring now more particularly to Fig. 4, a pipe line adapted to conduct fluid, is shown at reference numeral 73. A pipe 75 interconnects pipe line 73 with a pump 77, a constant temperature auxiliary heater 79, which may be omitted

if desired, and tine 3 of vibratory element 1. A pipe 81 connects the tine 5 to a temperature compensating unit 83. An outlet pipe 85 provides for fluid communication between the temperature compensator unit 83 and the pipe line 73.

The microphones 61 and 63, which are preferably of the pick-up coil type, are connected through a wire 87, a wire 89 and a condenser 91 to the input of a vibrator electronic drive unit I. These wires 87, 89 and condenser 91 supply the grid circuit of a vacuum tube 100. The circuit components of the tube 100 include a cathode resistor 101, a screen resistor 102, a screen bypass condenser 103, a plate load resistor 104, a plate bypass condenser 105, and a plate isolating resistor 106. The output of the tube 100 is transmitted through a coupling condenser 107 to the control grid of an amplifier tube 109. The circuit of the amplifier tube 109 includes a grid resistor 111, a cathode resistor 113, a decoupling condenser 115 and an isolating resistor 117. One output of tube 109 proceeds to the electromagnetic driver 57 through wires 119 and 121.

The other output of tube 109 is through a wire 123 to an automatic volume-control circuit including a diode tube 125, a battery 127 and a condenser 129. A feed-back circuit through a resistor 131 and a wire 133 is provided between the diode 125 and the grid return circuit of tube 109. The output of tube 109 is transmitted through a coupling condenser 135 to three amplifier tubes 137, 139 and 141. The circuit components of tube 137 include a resistor 138, a grid coupling condenser 140, a cathode resistor 143 and a winding 145 of a three phase transformer 147. The circuit components of tube 139 include a potentiometer 149, a cathode resistor 151 and a transformer winding 153. The circuit components of tube 141 include a resistor 155, a condenser 157, cathode resistors 158 and 159, and a transformer winding 160. A battery 161, or another suitable source of D. C. power, supplies D. C. energy through wires 163 and 165 to the various vacuum tubes and circuit components of the driver unit I. The three-phase output of the transformer 147 is connected through wires A to the stator of a three-phase selsyn motor, 167, shown at the lower left.

The output shaft 169 of the selsyn motor 167 is connected through gears 171 and 173 to an indicating device 175 on a shaft 177. Shaft 177 is adapted to drive a set of three variable resistors C-1, C-2 and C-3 in the temperature compensator unit 83 in an opposite direction to three similarly driven variable resistors D-1, D-2, and D-3. Variable resistors C-1, C-2, and C-3 are wound with negative resistance coefficient type wire while the inversely driven variable resistors D-1, D-2 and D-3 are wound with zero resistance coefficient type wire. By negative resistance coefficient type wire is meant wire which has its resistance decreased by an increase in temperature (or increased by a decrease in temperature). By zero resistance coefficient type wire is meant wire which has its resistance substantially unaffected by temperature. A set of three resistors E-1, E-2 and E-3 are connected in series with C-1 and D-1, C-2 and D-2, and C-3 and D-3, respectively. These six variable resistors and the three resistors are all enclosed in the temperature compensator unit 83 having a well containing resistors E-1, E-2 and E-3 immersed in the fluid. A set of three condensers 179, 181 and 183 in combination with the six variable resistors and three resistors of the temperature compensator unit 83 complete the

input network circuit for a phase shift oscillator unit II through wires 187, 188 and 189, and a condenser 191.

The phase shift oscillator unit indicated at 5 numeral II has components equivalent to the corresponding components of the driver unit I described above. Therefore, in the interest of brevity, the components of the phase shift oscillator unit II carry reference numerals corresponding as to the last two digits of the numerals of the respective equivalent components of vibratory driver unit I; the reference numerals of unit I, however, are prefaced by "1" and the reference numerals of unit II being prefaced by 10 "2." The operation, construction and circuits of 15 unit I are respectively identical with those of unit II with the single exception that there is no output taken from the plate of tube 209 as is taken from the plate of tube 109; the oscillatory circuit in unit II being completed by a wire 138. Because of this single circuit difference a plate 20 resistor 218 is added to supply a load to the tube 209 which resistor is equivalent to the electromagnetic driver 57 which is the load of tube 109. 25 The three-phase output of the phase shift oscillator unit II is connected to the rotor of the three-phase selsyn motor 167 by means of the wires B.

Operation is as follows:

30 A fluid, the density which is to be determined is initially caused to flow through pipe line 73. A portion of this fluid is by-passed through the pipe 75 and through the vibratory element or system 1. A relatively constant flow of this fluid is insured by the use of the pump 71. The fluid 35 may be maintained at a relatively constant temperature, if desired, by the use of the constant temperature unit 79. Referring to Figs. 1-3, the fluid is conducted through the conduit 11 to the interior of tine 3 to the tube 35. After passing upward in the direction of the arrows through tube 35 the fluid flows downward through the tine 3 and through the central channel of block 40 24 to the interior of tine 5 where it is conducted upward and through the perforations 45 of tube 45 43, and then downward in the direction of arrows and out through the conduit 23. The fluid then is conducted by the pipe 81, Fig. 4, to the temperature compensator unit 83 and is returned 50 to the pipe line 73.

55 Any casual noise or vibration will cause microphones 61 and 63 to produce an electrical signal which will be transmitted through wires 87 and 89 and condenser 91 to the input grid of tube 109 of the driver unit I. This signal is amplified by the tube 100 and fed through the coupling condenser 107 to the amplifier tube 109. The output of tube 109 through wires 119 and 121 energizes the electromagnetic driver 57 which in turn will actuate the tines 3 and 5 of the vibratory element 1. This movement of the tines 3 and 5 will be transformed into another signal being transmitted to the microphones 61 and 63, which will in turn, through the associated circuits of tubes 100 and 109 set up an oscillation, the frequency of which is dependent upon the natural resonant frequency of the vibratory system 1. If the density of the fluid flowing through the tines 3 and 5 remains constant this natural resonance frequency will not change.

60 In order to maintain the level of the signal through the oscillatory circuit at a relatively constant level the tube 125 has been employed. When the peak voltage of the oscillatory signal, 65 as measured at the plate of tube 109, reaches an

amplitude which exceeds a potential determined by battery 127, the diode tube 125 starts rectifying, thus impressing a negative bias on tube 100 through wire 133. Tube 100, which may be of the variable mu type, thus has its gain effectively controlled by the action of tube 125. The amplitude level of the oscillatory signal through tubes 100 and 109 is maintained substantially constant to deliver a relatively constant amplitude signal through the coupling condenser 140 to the tubes 139, 137 and 141.

The arrangement of tubes 137, 139 and 141 is such that the outputs of these three tubes as characterized by the signals in transformer windings 145, 153 and 160, will be 120° out of phase respectively one with the other. Thus the output phase of the signal on the plate of tube 137 lags the output signal on the plate of tube 139 by 60°. The phase of the plate signal on tube 141 leads that of the signal on plate of tube 139 by 60°. As the direction of windings 145 and 160 are inverse to the direction of winding 153 there will be a 120° phase difference between the outputs of these three windings. The potentiometer 149 provides a means for adjusting the amplitude of the signal of tube 139 so that the amplitudes of the three output phases are at all times equal.

The three-phase output of transformer 147 is fed to the stator of the selsyn motor 167. If the phase and the frequency of the input to the stator of motor 167 is identical with the phase and frequency of the output of transformer 247 to the rotor of selsyn motor 167, there will be no movement of the shaft 169. If, however, the frequency and the phase of the output A of the driver unit I differs from that of the output of the phase shift oscillator unit II, selsyn motor 167 will be energized and will operate until the output of the phase shift oscillator unit II corresponds in frequency and phase to the output of vibratory driver unit I. The phase and the frequency of the output of the phase shift oscillator circuit II is dependent upon the relative settings of the variable resistors C-1, C-2, C-3, D-1, D-2 and D-3. Thus upon a movement of shaft 177 by selsyn motor 167 these six variable resistors in the temperature compensator unit 83 are varied and cause a corresponding frequency and phase change in the input signal through wires 187 and 188 and 189 to the input circuit of tube 200. This signal is amplified by means of the tubes 200 and 209 together with their associated circuit components and by means of the lead 188 a feed-back circuit is established which maintains an oscillatory resonant circuit, the frequency of which is determined by the frequency of the input signal through the wires 187, 189 and 191. The amplitude level of this oscillatory signal is maintained substantially constant by the action of A. V. C. tube 225, and the three vacuum tubes 237, 239 and 241 provide a three-phase output signal across the windings 245, 253 and 260 respectively. The output of the three-phase transformer 247 is connected to the rotor of the three phase selsyn motor 167. Movement and the direction of movement of the selsyn motor 167 is therefore dependent upon any frequency and phase differences between the outputs of the vibratory driver unit I and that of the phase shifter oscillator unit II.

Thus it can be seen that any variation in the resonant frequency of the vibratory element I causes a corresponding variation in the output frequency of the driver unit I. This variation in

the output of driver unit I will cause a corresponding deflection of the indicating device 175, which is calibrated in absolute density units, and a change in the output frequency of the phase shift oscillator unit II. Under normal operating conditions the output of transformer 147 will be in phase respectively to the corresponding windings of transformer 247 and the frequency output to the rotor and the stator of the selsyn motor 167 will be the same. Only for a short period of time while the selsyn motor is actually in movement will the phase and frequency outputs of unit I be different from that of unit II.

Any variation in temperature of the fluid being measured will cause a variation in frequency. To insure a greater accuracy the temperature compensator unit 83 is provided. Variable resistors C-1, C-2 and C-3 are of negative coefficient wire and when the fluid temperature increases the resistance of these resistors will decrease causing a corresponding increase in frequency in the input signal to tube 200.

The density of the fluid flowing through vibratory element I will be similarly decreased which will cause a corresponding rise in vibratory frequency. Variable resistors C-1, C-2 and C-3 are so attached to shaft 177 that when the density of the fluid decreases the effective resistance of these resistors is greater which will give a greater amount of temperature compensation. The temperature-induced decrease in density of the fluid causes the vibratory frequency of element I to increase which causes a decrease in the effective resistance of variable resistors D-1, D-2 and D-3, which resistance decrease is relatively greater per degree of rotation of shaft 177, than the resistance increase of resistors C-1, C-2 and C-3. Thus, the net effect of the temperature compensator unit 83 is to insure that there will be no change in the absolute density reading as indicated by indicating device 175 when the change in density of the fluid is due solely to temperature variation and not to an actual density variation. It should be noted that the temperature compensator unit 83 is a network of variable and fixed resistances some of which are of negative coefficient wire. By proper connection of this network an effective non-linear or linear temperature compensation can be obtained. For example, where density is read on an A. P. I. scale, non-linear temperature compensation is desirable.

To calibrate the density meter of the present invention, the vibratory element or system I is filled with fluid of a known density at a temperature, and by proper manipulation of the adjustment nuts 55 of tines 3 and 5, the indicating device 175 is adjusted to give a density reading equal to that of the known density of the fluid at that temperature.

It is clear that the density indication at the member 175 may be transmitted to any remote point by known transmitter means. It is also clear that any indication in element 175 of deviation of density from some predetermined norm may be caused to set in motion mechanism for correcting the deviation. For example, if the deflection from a norm of the indicator 175 is too far in the direction of increased density, suitable means may be set into motion to introduce into the pipe 73 a fluid of lower density so as to average down the density of the resulting mixture. Or, if the deflection from a norm of the indicator 175 is too far in the direction of decreased density, suitable means may be set into

motion to introduce into the pipe 73 a fluid of higher density so as to average up the density of the resulting mixture. This is possible because of the continuously reading characteristics of the device, including continuous indications of fluctuations. Thus it will be seen that the present invention is useful not only for indicating density conditions, but provides means for initiating corrections of deviations from desired density conditions. An exemplary use would be in the petroleum industry where it is often desired to maintain a fuel oil output at a predetermined specific gravity (density). And whatever results are attained are independent of temperature fluctuations, which is of great importance in any application of the invention to practical ends such as outlined. A further example of such control in the petroleum industry is the shutting off of a valve in a pipeline where oil of one density is followed by oil of another density and it is desired to switch the oils into separate tanks.

It is to be understood that under conditions wherein the temperature of the fluid under investigation remains constant, there would be no need for a temperature corrective circuit such as II. In such event the output frequency of the lines A would be a measure of the natural frequency of the mechanical system (including fluid). Under such conditions these lines are to be connected to a frequency meter or the like not shown which when properly calibrated would read directly in terms of the density. Conversely, if the temperature corrective circuit is used, the temperature of the fluid need not be maintained substantially constant.

In view of the above, it will be seen that the several objects of the invention are achieved and other advantageous results attained.

As many changes could be made in the above constructions and methods without departing from the scope of the invention, it is intended that all matter contained in the above description or shown in the accompanying drawings shall be interpreted as illustrative and not in a limiting sense.

We claim:

1. A densimeter for measuring the density of fluids comprising a hollow vibratory mechanical system, circulating means for moving fluid through said system, said system including the contained fluid having a natural frequency of vibration, an electric driver for mechanically vibrating as a unit said system including the contained fluid at said natural frequency, electric pick-up means responsive to the vibrations of the system including the fluid, an electronic circuit responsive to said pick-up means and adapted to produce electrical oscillations in accordance with the mechanical vibrations and to energize said driver, said electronic circuit having a first output, a second electronic circuit having a second oscillatory output, and means adapted to indicate said natural vibratory frequency responsive to incipient frequency and phase differences between said first and second outputs to maintain the frequency and phase of said second output substantially the same as that of said first output.

2. A densimeter for measuring the density of fluids comprising a hollow vibratory mechanical system, circulating means for moving fluid through said system, said system including the contained fluid having a natural frequency of vibration, an electric driver for mechanically vibrating as a unit said system including the contained fluid at said natural frequency, electric

pick-up means responsive to the vibrations of the system including the fluid, an electronic circuit responsive to said pick-up means and adapted to produce electrical oscillations in accordance with the mechanical vibrations and to energize said driver, said electronic circuit having a first output, a second electronic circuit having a second output, means responsive to incipient frequency and phase differences between said first and second outputs to maintain the frequency and phase of said second output substantially the same as that of said first output, and indicating means actuated by said last-mentioned means to move in accordance with frequency variations of said first output and thus continuously to indicate the density of said contained fluid.

3. A densimeter for measuring the density of fluids comprising a hollow vibratory mechanical system, circulating means for moving fluid through said system, said system including the contained fluid having a natural frequency of vibration, an electric driver for mechanically vibrating as a unit said system including the contained fluid at said natural frequency, electric pick-up means responsive to the vibrations of the system including the fluid, an electronic circuit responsive to said pick-up means and adapted to produce electrical oscillations in accordance with the mechanical vibrations and to energize said driver, said electronic circuit having a first output, a second electronic circuit having a second output, means in said second circuit responsive to the temperature of the fluid adapted to vary the frequency and phase of said second output to compensate for temperature-induced density variations of said fluid, and means adapted to indicate said natural vibratory frequency responsive to incipient frequency and phase differences between said first and second outputs to maintain the frequency and phase of said second output substantially the same as that of said first output.

4. A densimeter for measuring the density of fluids comprising a hollow vibratory mechanical system, circulating means for moving fluid through said system, said system including the contained fluid having a natural frequency of vibration, an electric driver for mechanically vibrating as a unit said system including the contained fluid at said natural frequency, electric pick-up means responsive to the vibrations of the system including the fluid, an electronic circuit responsive to said pick-up means and adapted to produce electrical oscillations in accordance with the mechanical vibrations and to energize said driver, said electronic circuit having a first output, a second electronic circuit having a second oscillatory output, means in each of said electronic circuits for maintaining substantially constant the amplitude of the respective outputs, and means adapted to indicate said natural vibratory frequency responsive to incipient frequency and phase differences between said first and second outputs to maintain the frequency and phase of said second output substantially the same as that of said first output.

5. A densimeter for measuring the density of fluids comprising a hollow vibratory mechanical system, circulating means for moving fluid through said system, said system including the contained fluid having a natural frequency of vibration, an electric driver for mechanically vibrating as a unit said system including the

contained fluid at said natural frequency, electric pick-up means responsive to the vibrations of the system including the fluid, an electronic circuit responsive to said pick-up means and adapted to produce electrical oscillations in accordance with the mechanical vibrations and to energize said driver, said electronic circuit having a first output, a second electronic circuit having a second output, means in said second circuit responsive to the temperature of the fluid adapted to vary the frequency and phase of said second output to compensate for temperature-induced density variations of said fluid, means in each of said electronic circuit for maintaining substantially constant the amplitude of the respective outputs, and means adapted to indicate said natural vibratory frequency responsive to incipient frequency and phase differences between said first and second outputs to maintain the frequency and phase of said second outputs substantially the same as that of said first output.

6. A densimeter for measuring the density of fluids comprising a hollow vibratory mechanical system, circulating means for moving fluid through said system, said system including the contained fluid having a natural frequency of vibration, an electric driver for mechanically vibrating as a unit said system including the contained fluid at said natural frequency, electric pick-up means responsive to the vibrations of the system including the fluid, an electronic circuit responsive to said pick-up means and adapted to produce electrical oscillations in accordance with the mechanical vibrations and to energize said driver, said electronic circuit having a first output, a second electronic circuit having a second output, means responsive to any incipient differences between the frequencies and phases of said two outputs adapted to move in accordance with said differences but to maintain an assumed position when said frequencies and phases are identical, whereby the density of said contained fluid is continuously indicated.

7. A densimeter for measuring the density of fluids comprising a hollow vibratory mechanical system, circulating means for moving fluid through said system, said system including the contained fluid having a natural frequency of vibration, an electric driver for mechanically vibrating as a unit said system including the contained fluid at said natural frequency, electric pick-up means responsive to the vibrations of the system including the fluid, an electronic circuit responsive to said pick-up means and adapted to produce electrical oscillations in accordance with the mechanical vibrations and to energize said driver, said electronic circuit having a first output, a second electronic circuit having a second output, and means fed by said first and second outputs adapted to move only when either the frequencies or phases of said outputs are unequal, the frequency and phase of the second circuit being responsive to the movement of said means, whereby the density of said contained fluid is indicated.

8. A densimeter for measuring the density of fluids comprising a hollow vibratory mechanical system, circulating means for moving fluid through said system, said system including the contained fluid having a natural frequency of vibration, an electric driver for mechanically vibrating as a unit said system including the contained fluid at said natural frequency, electric

pick-up means responsive to the vibrations of the system including the fluid, an electronic circuit responsive to said pick-up means and adapted to produce electrical oscillations in accordance with the mechanical vibrations and to energize said driver, said electronic circuit having a first output, a second electronic circuit having a second output, means in said second circuit responsive to the temperature of said fluid to compensate for temperature-induced density variations of said fluid, and means fed by said first and second outputs adapted to move only when either the frequencies or phases of said outputs are unequal, the frequency and phase of the second circuit being responsive to the movement of said means, whereby the density of said contained fluid is indicated.

9. A densimeter for measuring the density of fluids comprising a hollow vibratory mechanical system, circulating means for moving fluid through said system, said system including the contained fluid having a natural frequency of vibration, an electric driver for mechanically vibrating as a unit said system including the contained fluid at said natural frequency, electric pick-up means responsive to the vibrations of the system including the fluid, an electronic circuit responsive to said pick-up means and adapted to produce electrical oscillations in accordance with the mechanical vibrations and to energize said driver, said electronic circuit having a first output, a second electronic circuit having a second output, means in said second circuit responsive to the temperature of said fluid to compensate for temperature-induced density variations of said fluid, electronic means in each of said circuits for maintaining substantially constant the amplitude of the respective outputs, and means fed by said first and second outputs adapted to move only when either the frequencies or phases of said outputs are unequal, the frequency and phase of the second circuit being responsive to the movement of said means, whereby the density of said contained fluid is indicated.

10. Apparatus for responding to the density of fluids comprising a hollow vibratory system adapted to contain a fluid the density of which is to be determined, said system including a contained fluid and having with said fluid a natural vibratory frequency of resonance, an electric driver for mechanically vibrating as a unit said system including the contained fluid at said natural frequency, electric pick-up means responsive to the vibrations of the system including the fluid, a regenerative circuit connected between the pick-up means and the driver and feeding an output, and frequency responsive means connected with said output.

11. Apparatus for responding to the density of fluids comprising a hollow vibratory system adapted to contain a fluid the density of which is to be determined, said system including a contained fluid and having with said fluid a natural vibratory frequency of resonance, an electric driver for mechanically vibrating as a unit said system including the contained fluid at said natural frequency, electric pick-up means responsive to the vibrations of the system including the fluid, a regenerative circuit connected between the pick-up means and the driver and feeding an output, means in said circuit for maintaining substantially constant the amplitude of the oscillations therein, and frequency responsive means connected with said output.

12. Apparatus for responding to the density of fluids comprising a hollow vibratory system adapted to contain a fluid the density of which is to be determined, said system including a contained fluid and having with said fluid a natural vibratory frequency of resonance, an electric driver for mechanically vibrating as a unit said system including the contained fluid at said natural frequency, electric pick-up means responsive to the vibrations of the system including the fluid, a regenerative circuit connected between the pick-up means and the driver and feeding a first output, a phase-shift oscillator circuit having a second output, and means connecting said outputs responsive to phase and frequency differences between the outputs to move in a direction to cancel said phase and frequency differences.

13. Apparatus for responding to the density of fluids comprising a hollow vibratory system adapted to contain a fluid the density of which is to be determined, said system including a contained fluid and having with said fluid a natural vibratory frequency of resonance, an electric driver for mechanically vibrating as a unit said system including the contained fluid at said natural frequency, electric pick-up means responsive to the vibrations of the system including the fluid, a regenerative circuit connected between the pick-up means and the driver and feeding a first output, a phase-shift oscillator circuit feeding a second output and having a temperature-responsive circuit component, means connecting said outputs responsive to phase and frequency differences between the outputs to move in a direction to cancel said phase and frequency differences, said temperature-responsive component and the fluid being in heat exchange relationship.

14. Apparatus for responding to the density of fluids comprising a hollow vibratory system adapted to contain a fluid the density of which is to be determined, said system including a contained fluid and having with said fluid a natural vibratory frequency of resonance, an electric driver for mechanically vibrating as a unit said system including the contained fluid at said natural frequency, electric pick-up means responsive to the vibrations of the system including the fluid, a regenerative circuit connected between the pick-up means and the driver and feeding a first output, a phase-shift oscillator circuit feeding a second output and having a temperature-responsive circuit component, means connecting said outputs responsive to phase and frequency differences between the outputs to move in a direction to cancel said phase and frequency differences, said temperature-responsive component and the fluid being in heat exchange relationship, and means in each of said

circuits for maintaining constant and equal the amplitudes of the oscillations therein.

15. Apparatus for responding to the density of fluids comprising a hollow vibratory system 5 adapted to contain a fluid the density of which is to be determined, said system including a contained fluid and having with said fluid a natural vibratory frequency of resonance, circulating means for moving fluid through said system, an 10 electric driver for mechanically vibrating as a unit said system including the contained fluid at said natural frequency, electric pick-up means responsive to the vibrations of the system including the fluid, a regenerative circuit connected 15 between the pick-up means and the driver and feeding an output, and frequency responsive means connected with said output.

16. Apparatus for responding to the density of fluids comprising a hollow vibratory system 20 adapted to contain a fluid the density of which is to be determined, said system including a contained fluid and having with said fluid a natural vibratory frequency of resonance, an electric driver for mechanically vibrating as a unit said system including the contained fluid at said natural frequency, electric pick-up means responsive 25 to the vibrations of the system including the fluid, a regenerative circuit connected between the pick-up means and the driver and feeding an output, means in said circuit for maintaining substantially constant the amplitude of the oscillations therein, frequency responsive means connected with said output, and means responsive to the temperature of said fluid to vary the frequency of said oscillations 30 to compensate for temperature induced density variations of said fluid.
